UNITED STATES PATENT OFFICE.

CHARLES M. ROSE, OF NEW YORK, N. Y.

TELEPHONE-CALL RECORDER.

1,140,070.

Specification of Letters Patent.

Patented May 18, 1915.

Application filed July 11, 1914. Serial No. 850,385.

To all whom it may concern:

Be it known that I, CHARLES M. ROSE, a citizen of the United States, residing in the city of New York, borough of Manhattan, in the county and State of New York, have invented a certain new and useful Improvement in Telephone-Call Recorders, of which the following is a specification.

The invention relates to means for recording by a subscriber the number and location of telephone calls made, and the object of the invention is to provide a simple, easily operated device by which the total number of calls made is registered, the exchange and number of each call recorded, and unanswered calls marked or canceled, so that an exact record of calls may be conveniently kept by the subscriber to serve as a check on the periodical bills for telephone service.

The invention consists in certain novel features of construction and arrangement by which the above objects are attained, to be hereinafter described and claimed.

The accompanying drawings form a part of this specification and show an approved form of the invention.

Figure 1 is a side elevation of the recorder. Fig. 2 is a plan view. Fig. 3 is a corresponding plan view with the cover removed. Fig. 4 is a central vertical section, taken on the line 4—4 in Fig. 3, and partly in elevation. Fig. 5 is a similar view of the working portions of the device, taken on the line 5—5 in Fig. 3 and seen in the direction indicated by the arrows. Fig. 6 is a corresponding end view.

Similar letters of reference indicate the same parts in all the figures.

A is a casing preferably of sheet metal stamped to the form shown, having lugs A¹ A¹ by which it may be attached to the wall or other surface, and a cover A² having a hinged portion A³ arranged to be raised to permit access to the interior of the casing. The fixed portion A² of the cover has an opening a through which the figures on the numbered disks of a counter B may be read, and the hinged portion A³ has two openings a¹ a², the first, a¹, affording access to a strip or wide tape of paper M and permitting the number and exchange of the called subscriber to be written thereon, and the other, a², permitting the last previous call thus written to be seen when the strip is advanced.

The strip is fed through a slot a³ to the exterior at the rear, formed by the lips A⁴ and A⁵ on the casing and cover respectively.

Within the casing and matching the interior thereof is a framework composed of two side-plates C C joined by bars C¹ C² near the front and carrying the mechanism operated by the push-pins D² D³ standing vertically side by side and extending downwardly through the fixed portion A² of the cover. The push-pins are extensions of square slides D D¹ mounted and guided in the bars C¹ C², each having a forwardly projecting pin or arm marked D⁴ D⁵ respectively, adapted when either slide is depressed to engage the cross-bar E of a tilting frame pivoted between the plates C C at c c and correspondingly raise the rearwardly extending lever E¹ forming a continuation of the frame on one side thereof.

In the end of the lever E¹ is a slot e receiving a pin F² set in the end of an arm F¹ extending from a clutch or series of spring pawls F loosely mounted on a shaft G and adapted to engage a series of slots formed in the adjacent face of a gearwheel G¹ fixed on the shaft G, and partially rotate the gearwheel as the arm F¹ is thus raised. The slot e provides the required lost motion for the pin F² in the variation of angle caused by the lifting of the lever E¹ and arm F¹.

The spring pawls and slotted wheel, imperfectly shown, is a well-known means of inducing a step-by-step movement and is preferred in this device. It comprises a flat plate of spring metal loosely encircling the shaft G and lying face to face with the gearwheel G¹, having three concentric arms serving as spring pawls each formed with a slight set toward the gearwheel G¹ which latter has a concentrically arranged series of slots each adapted to permit the end of either arm or pawl to engage therein. By raising the lever E¹ the plate is rotated on the shaft G and one or more of the arms in engagement with the slots will cause the gearwheel G¹ to make a partial rotation. The depression of the lever E¹ causes the plate and its arms to return idly for a succeeding engagement in succeeding slots, the gearwheel G¹ being held by its frictional engagement with the pinion G² against partaking in such reverse movement. Other means, as the ordinary ratchet and pawl, may be substituted.

In mesh with the gearwheel G^1 is an idle pinion G^2 meshing with a pinion G^3 on the shaft of a roller G^4 and rotating the latter in the desired direction at each depression 5 of either of the push-pins. Above the roller G^4 is a similar roller G^5 removably mounted in the plates C C , the ends of its shaft G^6 being received in vertical slots c^1 c^2 in such plates, and held in strong frictional contact 10 upon the lower roller by springs A^6 secured to the under face of the cover A^3 and bearing upon the ends of the shaft G^6 . Both rollers are rubber faced to afford the required grip on the strip M passing between 15 them to effect the desired feed.

Between the plates C C is a platform H having a downwardly extending flange H^1 at each side and pivotally mounted on a transverse stud C^3 joining the plates C C . 20 The flanges H^1 H^1 are notched as at h to receive the ends of a shaft H^2 forming the core of a coil or roll of paper M on which the record of calls is written. The strip or wide tape extends from the roll upwardly 25 over a loose sleeve or roller C^4 on the stud C^3 to the upper face of the platform H which lies parallel with and immediately beneath the hinged cover A^3 , and thence between the rollers G^4 G^5 and passes out of 30 the casing through the slot a^3 above described, traveling between the platform H and cover A^3 , thus presented at the openings a^1 a^2 in the latter and supported by the platform. 35 The counter B is of any suitable type, attached by an arm B^1 to the upper bar C^1 and having its numbered disks presented at the opening a as above described. Its shaft B^2 projects at one side and carries an arm B^3 40 extending through a vertical slot d in the slide D of such length as to provide the stroke required to move the disks at each depression of the push-pin D^2 .

When a call is to be made the call number 45 and exchange desired is written by the subscriber upon the strip M through the opening a^1 ; after the call is answered and the conversation ended, the subscriber depresses the push-pin D^2 , marked for convenience 50 "Record", which turns the counter one number in advance through the action of the arm B^3 and moves the strip M through the action of the rollers G^4 and G^5 operated by the frame E , lever E^1 , arm F^1 and gearwheel and pinions to present the writing at 55 the opening a^2 . In this manner the record may be kept and unanswered calls canceled by crossing off or otherwise marking the strip at the opening a^1 or a^2 , and at the 60 end of the month or other period, subtracting the number of calls thus canceled from the total number shown by the counter, the remainder showing the calls to be paid for. To avoid this calculation a canceling device 65 is included in the apparatus. The slide D^1

operated by the push-pin D^3 marked "Shift", carries the arm D^5 to engage the crossbar E and operate the feed rollers G^4 G^5 but has no connection with the counter. A lever K pivoted to the side-plate C at k 70 lies in the path of the slide D^1 and is struck by the latter at the end of its downward travel; its opposite arm carries a pin K^1 engaged in a slot l in a lever L extending from a sleeve L^1 loosely mounted on the 75 shaft G of the gearwheel G^1 , and the sleeve carries an upwardly extending arm L^2 terminating in a sharp point L^3 arranged when tilted to strike through a narrow slot h in the platform H below the opening a^2 and 80 perforate the strip M and thus mark the latter. A bridge A^7 having an aperture a^3 lies across the opening to hold the strip against the lifting force of the perforating point and insure the marking. 85

After the call number and exchange has been noted on the strip at the opening a^1 , as above described, if the party called is not found the push-pin D^3 is depressed which feeds the strip to present a fresh surface at 90 the opening a^1 and to present the noted call at the opening a^2 without operating the counter, and at the same time drives the point L^3 through the strip into the aperture a^3 thus registering the fact that the call was 95 not answered. The counter then shows only the number of calls to be paid for during the period, and in case of any question as to the number and location of calls the strip shows an exact record of those answered and 100 unanswered.

The hinged cover A^3 and platform H , with the removable upper roller G^5 permit a new roll of paper to be easily inserted and threaded, and allows access to the mechanism. 105

Helical springs D^6 and D^7 return the slides and push-pins to position, and the leaf springs E^2 and K^2 return the levers E^1 and K to their idle positions. 110

A^8 is a stop supporting the platform H in its lowered position.

I claim:

1. In a device of the character set forth, a casing having a record opening and a cancellation opening therein, one in advance of the other, a strip of paper within said casing, a feeding mechanism for moving said strip, a counter, a push-pin and means actuated by the latter for operating said counter and feeding mechanism, whereby an inscription written on said strip at the record opening is subsequently presented for verification or for cancellation at the cancellation opening by the action of said feeding mechanism. 115

2. In a device of the character set forth, a casing having a record opening and a cancellation opening therein, one in advance of the other, a strip of paper within said casing and 120

presented at such openings, a feeding mechanism for moving said strip, a counter, a pair of push-pins, mechanism actuated by either of said push-pins for operating said feeding mechanism, and means actuated by one of said push-pins alone for also operating said counter, whereby an inscription written on said strip at the record opening is presented at the cancellation opening for verification and is registered by the counter, or for cancellation without such registration.

3. In a device of the character set forth, a casing having a record opening and a cancellation opening therein, one in advance of the other, a strip of paper within said casing and presented at such openings, a feeding mechanism for moving said strip, a counter, a pair of push-pins, mechanism actuated by either of said push-pins for operating said feeding mechanism, means actuated by one of said push-pins alone for also operating said counter, and means actuated by the other of said push-pins alone for marking said strip at said cancellation opening, whereby an inscription written on said strip at the record opening is presented at the cancellation opening for verification and is registered by the counter, or for cancellation by such marking without such registration.

4. In a device of the character set forth, a casing, a cover therefor having a record opening and a cancellation opening therein, one in advance of the other, a platform be-

neath said cover adapted to carry a rolled strip of paper extended along said platform and presented at such openings, rollers in said casing for feeding said strip, a counter, a push-pin and means actuated by the latter for operating said counter and feed rollers whereby an inscription written on said strip at said record opening is presented for verification or cancellation at said cancellation opening.

5. In a device of the character set forth, a casing, transverse bars therein, a pair of slides mounted in said bars, arms on said slides, a rolled strip of paper in said casing, feed rollers for said strip, a tilting frame in said casing arranged to be engaged by said arms and actuate said feed rollers by the movement of either slide, a counter and actuating connections therefrom to one of said slides, means actuated by the movement of the other of said slides for perforating said strip, a lever arranged with one end in the path of one of said slides, a lever for actuating said perforating means, and a loose connection between the adjacent ends of said levers.

In testimony that I claim the invention above set forth I affix my signature, in presence of two witnesses.

CHARLES M. ROSE.
